(57) **CLAIM**

The ornamental design for a football helmet, as shown and
described.

DESCRIPTION

FIG. 1 is a right side perspective view of the football helmet
embodying my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right elevational view thereof; and,

FIG. 7 is a left elevational view thereof.

The face mask shown in broken lines in the figures are for
illustrative purposes only and form no part of the claimed
design.
